UNITED STATES PATENT OFFICE

BRUNO BORNKESSEL, OF ESSEN, GERMANY, ASSIGNOR TO FRIED. KRUPP AKTIENGESELLSCHAFT, OF ESSEN-ON-THE-RUHR, GERMANY

PRINTING MECHANISM FOR CASH REGISTERS

Application filed April 26, 1926, Serial No. 104,822, and in Germany July 16, 1925.

The invention relates to printing mechanisms for cash registers, with which the impression of the set type wheels on a record strip and a check is effected by means of one and the same platen and, in particular, the printing of the check is capable of being effected selectively by means of different adjusting means which are independent of one another.

10 The essence of my invention resides in the fact that the actuation of the platen to print the check and the record strip is effected by actuating elements rigidly connected to one another and adapted to be changed over, 15 while the actuation of the check cutting and perforating mechanism, the record strip feed mechanism and the adjusting device for the impression of the date are effected by means which work unchangedly on every operation 20 of the machine.

In comparison with known arrangements of the character stated, in which each individual device of the complete printing mechanism is operated by an independently controlled actuating means, my novel mode of operating the individual devices offers the advantage of greater simplicity and clearness of arrangement.

25 The invention will now be described in detail with reference to the accompanying drawings which form part of this specification and illustrate, by way of example one embodiment of the subject-matter of my invention, a printing mechanism issuing a stub check.

In these drawings:

Fig. 1 is an elevation, partly in section, of the complete printing mechanism, one side wall of the frame work being removed,

30 Fig. 2 is the corresponding plan view,

Fig. 3 is a section on line III-III of Fig. 1;

Fig. 4 shows a special key and the means connecting it with the member controlling the impression onto the check,

35 Fig. 5 shows the adjusting means for the impression of the date,

Figs. 6 to 8 shows means actuating individual devices of the printing mechanism,

Fig. 9 is a sectional view of the check cutting and perforating device,

Fig. 10 is a cross section of Fig. 9,

Fig. 11 shows a stub check as issued by the mechanism,

55 Fig. 12 is a section on the line 12-12 of Fig. 2.

Referring now to Fig. 1 of these drawings, 1 denotes the record strip fed from a supply spool 2 and led over a hub 3 and a roller platen 4 to the storage spool 5. 6 denotes a check paper strip led from a supply spool 7 to the feeding and cutting mechanism by a guide 8. An impression is effected on said record strip on each operation of the machine.

60 The feeding mechanism 9, Fig. 1, for the record strip, which is of known construction, is operated by a rod 10 linked to a four-armed lever 12 loosely rotatable on a fixed shaft 11. The lever 12 co-operates by two rolls 13, 14, Fig. 6, with two cam disks 16, 17 rigid on a drive shaft 15. The fourth arm of lever 12 has linked to it a rod 18 the other end of which is pivotally connected by a pin 19 to an arm 21 mounted for rotation on a shaft 20, and to a link 22. Pin 19 carries a spring pawl 23 which co-operates with a ratchet wheel 26 fixed to the roll 24, Fig. 1, which inks and feeds the ink ribbon 25. Link 22, Figs. 6 and 1, is pivotally connected 70 to an arm 28 rigid on a shaft 27. On a second arm 29 rigid on shaft 27, Fig. 1, is linked a spring pawl 30 which co-operates with a ratchet wheel 31 imparting feed motion to the type wheels for the consecutive number. 75 A spring-actuated counter pawl 33 loose on a shaft 32, Fig. 1, prevents the ratchet wheel 31 from turning backward.

80 Upon the drive shaft 15 rotating clockwise, Fig. 6, the lever 12 has imparted to it, at the beginning of each operation of the machine, a single to and fro rocking motion starting clockwise, by means of the cam disks 16, 17, thus feeding the record strip 1, ink ribbon 25 and number ratchet wheel 31.

85 On a shaft 36 mounted in the side walls 34, 35, Fig. 3, of the frame are arranged six type wheels 37 for the amounts, four type wheels 38 for the consecutive number and four type wheels 39 for the date.

100

The amount type wheels 37 are connected in a well-known manner by nested tubes 40, 41 and intermediate pinions 42, 43 with the differential mechanism of the machine. The units wheel of the type wheels 38 for the consecutive number has fixed to it the above-mentioned ratchet wheel 31 feeding said type wheels 38. Shaft 36 has a recess 44, Figs. 3 and 1, located in the range of type wheels 38 and causing them, in a well-known manner, to return to zero, when shaft 36 is rotated by manipulating the knurled button 45 laterally projecting from the mechanism.

The date type wheels 39 co-operate with pinions 46, Fig. 5, engaging the gaps between the types of said wheels. The pinions 46 are further connected in a well-known manner by nested tubes 47, Fig. 3, with setting buttons arranged outside the frame work. The date wheels 39 are mounted on a sleeve 48, Figs. 5 and 3, the shell surface of which is normally concentric to shaft 36 while its bore is eccentric thereto, and which is connected to a pitman 54 by an arm 49, Fig. 5, rigid on it, a link 50, an arm 51, a shaft 52 and an arm 53 rigid on the latter. Pitman 54 embraces by its bifurcated end the drive shaft 15 and engages by a roll 55 a curved groove 56 of cam disk 17. The space left between sleeve 48 and shaft 36 is occupied by another eccentrically bored sleeve 57 rigid on the frame wall 34, Fig. 3, and thus prevented both from rocking with sleeve 48 and rotating with shaft 36.

The types of the date wheels 39, when set into the printing path opposite to roll 4, Fig. 1, are normally kept at the same distance away from said roll as the set types of the other type wheels, so that, upon the roll 4 executing a printing motion, also an impression of the set date is produced. Upon drive shaft 15 rotating, pitman 54, Fig. 5, however, has imparted to it one single rocking motion towards the right, thus rocking the eccentric sleeve 48 anti-clockwise and withdrawing the set types from roll 4 to such an extent that an impression of the date onto the record strip does not take place.

The cutting mechanism comprises a cylindrical knife 58, Figs. 9, 10, 1, which is mounted for rotary motion in a sleeve 59 and connected by an arm 60, Fig. 7, a link 61, a double lever 63 loose on a fixed shaft 62, and a rod 64 to an oscillating lever 65, which co-operates by rolls 66, 67 with two cam disks 68, 69 rigid on drive shaft 15. The knife 58 has a slot for the passage of the check paper. Its right-hand upper edge 70, Fig. 10, forms the cutting edge and co-operates with the companion knife 71 fixed on sleeve 59. The lower edge opposite to edge 70, of knife 58, forms a perforating punch 72. The cam disks 68, 69 are of a configuration such as to cause the knife 58 to turn once on each operation of the machine in

anti-clockwise direction and back in clockwise direction. With this first-named motion the perforation 73 of the check paper 74 is effected, as indicated in Fig. 11, between the two impressions, while by said backward motion of knife 58 the check is sheared off. When no check is to be issued in an operation, the free edge of the check paper remains located on the level of knife edge 70 and punch 72.

In contradistinction to the above-described mechanisms the means operating the roll 4 and the check feed mechanism are arranged so as to be shifted to modify the printing and check-feeding operations. These means comprise two cam disks 75, 76, Figs. 2 and 3, causing a three times printing motion, two cam disks 77, 78 causing a single printing motion of roll 4, a pinion 79 and two locking disks 80, 81 for the check feed. These means are arranged on a drum 82, Figs. 2 and 3, connected to drive shaft 15 by splines 83 so as to be shiftable thereon. On its one end the drum 82 has a switch collar 84, Fig. 2, recessed at 85, the rear wall 86 of said recess being peaked. With said collar 84 co-operates an adjusting pin or lug 87 fixed on a bolt or rod 89 shiftable in the walls 34, 35 but secured against rotation by a lock pin 88. A spring 90 normally keeps rod 89 in the inoperative position shown in Fig. 2 in which no check is issued. A knurled button 91 serves as a knob for pushing rod 89 against the action of spring 90 into operative position causing a stub check to be issued, the lug 87 assuming then the position shown in Fig. 2 in dotted lines. The button 91 is fixed for limited rotation on rod 89 and has an arm 92 adapted to engage a lug 93 fixed to the wall 34 and thus to keep rod 89 in operative position. On its other end rod 89 carries a flange 94 under which engages an angle lever 95 pivoted on wall 35. A link 96, Figs. 2 and 4, connects the free arm of lever 95 to a double lever 97 acted upon by a special key 98 selecting the line of business or the like of the machine. Upon depression of key 98, rod 89 is shifted into operative position against the action of spring 90 and remains therein until the depressed key 98 is released. In the position of rest the recess 85 enables lug 87 to be pushed into operative position. As soon as the drive shaft 15 is set in motion, then according to the position of rod 89 the upper or lower slope face of the peaked end 86, Fig. 2, of recess 85 strikes lug 87, whereby the drum 82 is shifted into operative or inoperative position at the beginning of the operation. During the further course of the operation drum 82 and rod 89 remain locked in their mutual positions owing to lug 87 abutting against the respective side face of collar 84.

The roll 4, Figs. 1, 2, 8, is carried on arms 100, 101 adapted to rock on shaft 99 and con-

nected by hub 3. Arm 100 has linked to it a thrust-rod 102, Fig. 8, connected by an arm 103 of shaft 11 to swing arms 105, 106 co-operating with the cam disks 75 to 78 by rolls 107, 108.

When drum 82 is in inoperative position, Fig. 2, the cam disks 77, 78 are engaged by the rolls 108, 107, respectively, and impart one single printing motion to roll 4 during the operation of the machine. With drum 82 in operative position, however, the rolls 107, 108 co-operate with the cam disks 76, 75, respectively, whereby three printing motions are imparted to roll 4 during the operation of the machine.

The mechanism feeding the check paper, Fig. 1, comprises a feed roller 109 and a companion roller 111 co-operating therewith by its collar 110 which determines the length of the check. The feed roller 109 has rigid on it a pinion 112 in mesh with a pinion 113 fast on shaft 62. The latter has further rigid on it a pinion 114, Figs. 1, 2, three teeth of which, 156, 157, 158, are cut away for a certain part of its width.

With drum 82 in operative position, the pinion 79 co-operates with the unmutilated portion of pinion 114 and the locking disk 80 with the mutilated portion. The teeth of pinion 79 are likewise mutilated and arranged in three groups, 159, 160, 161, so that a three step motion is imparted to pinion 114 upon shaft 15 rotating. The locking disk 80 has three cut away portions, 150, 151, 152, and three full circumferential portions, 153, 154, 155. During the intervals between the individual steps of motion and in the position of rest of the machine the pinion 114 is locked by the full circumferential portions of locking disk 80 engaging the gaps of pinion 114 formed by the cut away teeth 156, 157, 158. During the turning of pinion 114 its teeth are freed by the cut away portions of disk 80. The single revolution of shaft 15 causes the feed roller 109 to execute likewise a single full revolution which takes place, due to the described gear connection, in three steps producing what may be called a manifold or stepwise feed motion of the check paper. The intervals formed by the stepwise motion of the check paper are filled by the perforating, printing and cutting operation.

With drum 82 in inoperative position, pinion 114 is out of mesh with pinion 79, but in mesh with locking disk 81 located beside disk 80. Said disk 81 has a full shell surface which projects into one of the gaps of pinion 114 so that, with the drum 82 in inoperative position, this pinion and therewith the feed roller 109 remain locked in their position of rest during the operation of the machine.

The mode of co-operation of the described individual devices constituting the complete printing mechanism, is as follows:

When rod 89 takes its inoperative position,

Fig. 2, drum 82 is secured in inoperative position, at the beginning of the operation of the machine, by lug 87 or is brought thereto if it had been set to operative position in the preceding operation. Now first the feed of the record strip, ink ribbon and consecutive number takes place by means of cam disks 16, 17, Fig. 6, and thereupon said single printing motion of roll 4 by means of cam disks 77, 78, this effecting an impression to be made on the record strip. As the date wheels 39 are being swung away by the curved groove 56, Fig. 5, during this printing motion, this impression on the record strip shows no date. During the operation, the knife 58, Fig. 9, has imparted to it a turning motion, but since the feed roller 109 remains locked, as pointed out above, no feeding of the check strip towards the knife 58 occurs so that a perforation or severance of a check does not take place.

When rod 89 takes its operative position, after being brought thereto by means of button 91 or key 98, drum 82 is secured, at the beginning of the operation, in operative position by lug 87 or is brought thereto if it had been set to inoperative position in the preceding operation.

The feed of the record strip, ink ribbon and consecutive number is then followed by the first step of motion of the check paper by means of pinion 79, and then by the perforation of the check by means of cam disks 68, 69, Fig. 7. About at the same time roll 4, coupled with cam disks 75, 76, executes its first printing motion effecting an impression on the record strip, the check paper, however still remains unimpressed, since it has not yet been fed up to the printing line. During this printing operation the date wheels 39 are being thrown out so that the impression made on the record strip shows no date.

The perforation is followed by the second step of motion of the check paper and thereupon by the second printing motion of roll 4, the first impression (the upper in Fig. 11) thus being made on the check. In the meantime the date wheels had been thrown in, so that this impression contains the date, like the subsequent impression. When the third step of motion of the check paper is completed, the roll 4 is rocked the third time to make the second impression on the check. Shortly after the operation is completed, knife 58 is turned clockwise, thus shearing off the stub check from the paper and allowing it to glide out of the issue slot.

I claim:

1. In a machine of the class described a printing mechanism including an actuating shaft, means for rotating said shaft, an actuating member shiftably but non-rotatably mounted on said shaft, a switch collar fast on said actuating member, a lug co-operating with said switch collar, and means for caus-

ing said lug to engage one or the other flank of said switch rim, whereby said actuating member may be held during rotation of said shaft in either of two positions longitudinally of said shaft.

2. In a machine of the class described a printing mechanism including an actuating shaft, an actuating member shiftably but non-rotatably mounted on said shaft, a switch collar fast on said actuating member, a recess in said collar, one of the walls limiting said recess being peaked, a lug, means for positioning said lug into the path of one or the other of the inclined faces of said peaked wall, whereby upon said shaft rotating said actuating member is shifted into one of its limit positions and secured therein.

3. In a machine of the class described and as specified in claim 1: Said means for adjusting said lug comprising a rod shiftably mounted in the machine-frame, a spring adapted to yieldingly keep said rod in one limit position, a key, means connecting said key with said rod, said key and connecting means being adapted to keep said rod in its other limit position while the key is depressed.

4. In a machine of the class described a mechanism for printing a check and a record strip including an actuating shaft, a mutilated gear, a full locking disk rigidly connected to said gear, said gear and disk being non-rotatably but shiftably mounted on said actuating shaft, a second mutilated gear, positive connections between the latter and the check feeding means, means for throwing said first-named mutilated gear or said disk into engagement with said second mutilated gear, whereby the check has imparted to it on each operation of the machine either a manifold feed motion or no feed motion at all.

5. In a machine of the class described a platen for printing a check and a record strip, actuating means therefor effecting a manifold printing motion of said platen for impression on check and record strip, type carriers for the impression of the date, means for rocking said carriers out of the range of said platen, and actuating means for said rocking means coordinated with said first-named actuating means and timed to render said date type carriers inoperative during the motion, of said platen effecting the impression on said record strip.

6. In a machine of the class described a platen, a type wheel-shaft, an eccentric sleeve on said shaft, means for so connecting said sleeve to the machine-frame as to secure it against rotation, a second eccentric sleeve, date type wheels loose thereon, and connections between said second sleeve and the main drive of the machine causing said second sleeve to be turned and said date type wheels to be rocked out of the range of said platen.

7. In a machine of the class described a check printing and issuing mechanism including a stationary sleeve, a shaft rotatable in said sleeve, a slot extending through said sleeve and said shaft, the two opposed edges of said shaft at one mouth of said slot being in the form of a knife edge and a perforating punch respectively, means for feeding a check strip through said slot, and means for oscillating said shaft in both directions from the position in which its slot registers with the slots of said sleeve, whereby the check is perforated or cut off depending upon the direction of the oscillation.

8. In a machine of the class described comprising a check and record strip printing device, adjustable actuating means for said printing device adapted to cause a single printing motion or a multiple printing motion, and means for selectively throwing said actuating means into either position of adjustment comprising a shifting member connected to said actuating means adapted to execute a motion at each operation of the machine, and a setting member adapted to be engaged by said shifting member during the motion of the latter and to shift or hold said shifting member, and thereby said actuating means, to one of their two positions of adjustment depending upon the position of said setting member.

9. In a machine of the class described, a check printing and issuing mechanism including a perforating punch and a knife mounted on a common support so as to face each other with a slot between them, complementary engaging means for said punch and for said knife, check strip feeding means, and driving means adapted to move said support to bring either said punch or said knife into cooperation with said complementary engaging means to punch or to sever said check strip.

The foregoing specification signed at Cologne, Germany, this 13th day of March, 1926.

BRUNO BORNKESSEL.
